UNITED STATES PATENT OFFICE.

THOMAS P. BROOKE, OF CHICAGO, ILLINOIS.

MOTOR.

1,210,409.

Specification of Letters Patent.

Patented Jan. 2, 1917.

Application filed August 1, 1912. Serial No. 712,799.

To all whom it may concern:

Be it known that I, THOMAS P. BROOKE, a citizen of the United States, residing at Chicago, in the county of Cook and State of Illinois, have invented certain new and useful Improvements in Motors, of which the following is a specification.

This invention relates to improvements in motors, and more particularly to aero-nautic motors.

It has also reference to improvements in internal combustion motors and to motors of the rectilinear type.

One of the objects of the invention is to provide an improved motor of this type, whereby the gyrotrational effects of the rotation of the parts will be balanced and the gyroscopic forces will be overcome.

Another object of the invention is to provide an improved rotary type of motor of this class in which the force of the explosion of the charge will exert an impulse on a movable piston head and a reaction upon a movable cylinder head, thereby utilizing the maximum power of the charge and resulting in a motor of the minimum weight of structure and of the highest efficiency and power having the greatest number of explosions per revolution.

35 A further object is to provide an improved rotary motor of this class and of the four cycle type comparatively light in structure and having means whereby an explosion will be produced on every complete revolution of the cylinder.

40 A further object is to provide an improved motor of this type in which the cylinders and the piston cranks will rotate at the same rate of speed.

45 Other and further objects will appear from the following specification and claims when taken in connection with the accompanying drawings, exemplifying the invention and in which—

50 Figure 1 is a side elevation of an improved motor of this type, constructed in accordance with the principles of this invention. Fig. 2 is a section taken on line 2—2, Fig. 1. Fig. 3 is a section taken on line 3—3, Fig. 2. Fig. 4 is a section taken on line 4—4, Fig. 2. Fig. 5 is a section taken on line 5—5, Fig. 3. Fig. 6 is a top plan view of the end of one of the cylinders. Fig. 7 is a section on line 7—7, Fig. 7. Fig. 8 is a section on line 8—8, Fig. 7.

Heretofore in the manufacture of aero-nautic motors of the rectilinear rotary type, that is, in those employing a plurality of cylinders secured together, the cylinders are made to revolve about a fixed shaft having 60 a crank pin offset from the shaft to cause a comparative reciprocatory motion of the piston, thereby forming a fixed abutment, so to speak, for the reaction or impact of the force of the explosion, with the result 65 that considerable power from the explosion is lost.

In the present invention provision has been made not only to produce the greatest number of explosions for each revolution 70 of the cylinder, but to also secure the maximum power from each explosion. To this end, there is provided in the present invention a rotary cylinder and a rotary crank for causing a relative reciprocation of the 75 piston, with the result that the force of every explosion is exerted directly upon two moving elements so that there will be an impulse upon the movable piston head and a reaction of the force on the end of the 80 movable cylinder, this result is accomplished partially by reason of causing the cylinder and crank shaft to which the piston is connected to rotate simultaneously in opposite directions and through other instrumentalities to be hereinafter described. The objectionable gyroscopic forces of the 85 rotating parts is overcome by constructing the motor in sections disposed to rotate in opposite directions and the rotary motion 90 of the respective sections is employed to impart rotary motion to the crank shaft of the other section and the parts are so connected that the crank shaft of each section will rotate in the same direction as the 95 direction of rotation of the other series of cylinders or section, but in a direction opposite to the direction of rotation of their respective sections.

In the form of the invention shown in 100 the drawings, the two sections of the motor are designated generally by the reference characters 10, 11 in Fig. 2 and these sections are preferably mounted to rotate about different axes and in opposite directions and 105 each section comprises a plurality of cylinders 12 disposed radially about the respective axes as shown more clearly in Figs. 1 and 2. The cylinders are preferably of the same construction and are provided with 110

shoulders 13 adjacent the respective axes having inwardly extending flanges 14 preferably of segmental shape extending about the axis to form a substantially continuous flange. Securing flanges 15 are arranged between each pair of cylinders which are fastened by suitable fastening devices 16. Cover plates 17 are secured to extend over the flanges 14 to form an air and gas tight crank case. A hollow piston 18 is arranged to reciprocate in each cylinder and the piston rods 19 of one series of pistons are pivotally connected to a revolving crank pin 20 on a revolving shaft 21 while the piston rods 19 of the other series of pistons constituting the other section of the motor are connected with a revolving crank pin 22 on a revolving shaft 23. These crank shafts 21, 23 are rotatably journaled in suitable bearings in a supporting member 24^a (see Fig. 2) and the shafts as well as the crank pins are offset with relation to each other, that is, one is arranged above the other so that the sections of the motor will balance each other.

Motion is imparted to the various parts as follows: from the crank 22 to the shaft 23, to gear 31, then to gear 30, shaft 21, sprocket gear 24, sprocket gear 26, to crank of section 11 of the motor and then to shaft 65. At the same time motion will be imparted from the crank pin 20 to shaft 21, then to sprocket gear 24, sprocket gear 26, to crank case of motor section 11 and then to shaft 65. Motion is also imparted from the crank case of the motor section 10 to the sprocket gear 29, to sprocket gear 27, to shaft 23, to gear 31, to gear 30, to shaft 21, to gear 24, to gear 26, to crank case of the section 11 of the motor and then to the shaft 65. The shaft 65 also has power applied thereto directly by the rotation of the section 11 of the motor. Thus, it will be seen that power is applied from all of the rotating sections to the work shaft 65, that the sections 10 and 11 will rotate in the directions opposite to the directions of rotation of their respective crank shafts. Furthermore, the force of the explosion in every cylinder will act upon two movable elements, such as the movable pistons and the respective movable cylinder heads, thus obtaining the maximum force from the explosion, while at the same time there will be produced in each cylinder of this four cycle motor, an explosion upon every complete revolution of the cylinder. To accomplish this rotation of the cylinders and cranks, there is secured to the shaft a sprocket gear 24 which is connected by a sprocket chain 25 to a sprocket gear 26 (see Fig. 2) carried by the crank case of the series of cylinders or section 11 of the motor. A similar sprocket 27 is secured to rotate with the shaft 23 and is connected by a sprocket

chain 28 with a sprocket gear 29 secured to rotate with the crank case of the series of cylinders or section 10 of the motor. A gear 30 is secured to the shaft 21 to rotate therewith, while a gear 31 is carried by the shaft 23 and meshes with the gear 30. Thus it will be seen that with this connecting mechanism the desired result as to the direction of rotation of the parts as above described will be obtained, while the parts may be compactly arranged and in such a manner that access may be readily had thereto. The shafts 21, 23 are hollow and one has communication with each of the crank cases and serve as means whereby the explosive fluid may be supplied to the cylinders through the respective crank cases from a suitable carburetor (not shown). The fluid enters the shaft 21 through openings 32 from a chamber 33 in the support, while the shaft 23 is provided with openings for receiving the fluid from the chamber 35.

Each piston is provided with a passageway 36 connecting the explosion chamber 37 between each piston and the outer end of the cylinder with a gaseous mixture chamber within the cylinders on the inner sides of the piston. The passage of the gaseous mixture into the explosion chamber 37 is controlled by a valve 38 adapted to open outwardly when the piston moves inwardly and is provided with a stem 39 reciprocably mounted in a spider 40 in the passageway 36. Spaced collars 41, 42 are arranged on the inner end of the stem and a spring 43 is arranged between one of the collars and the spider to hold the valve lightly to its seat and is only of sufficient strength to hold the valve to its seat when the motor is not in operation. Counterbalancing levers 44 are pivoted intermediate their ends as at 45 so that one end will project between the collars 41, 42 and are weighted at their other ends so that when the cylinders revolve about their axes the weights will cause the valve 43 to be seated and held upon their seats by centrifugal force. The counterweights are of such a size as to slightly overbalance the weight of the valve but of just a suitable weight to permit the valve to open by suction when the piston moves inwardly to permit the entrance of a charge of fluid into the explosion chamber 37. Each cylinder is provided with an outlet opening 46 having a removable plug 47 secured therein and which plug is provided with a valve opening 48 controlled by an inwardly opening valve 49, the stem 50 of which moves through a spider 51. A spring 52 holds the valve to its seat when the motor is dead. An upright 53 is supported by the cylinder and a lever 54 is pivoted intermediate its ends as at 55 and is pivotally connected as at 56 with the end of the valve stem, while an operating rod 57 is pivotally connected with 130

the other end of the lever 54. This rod passes through a suitable bearing 58 (see Figs. 7 and 8) into the crank case and is provided with means, such as an anti-friction roller 59 by means of which it may be shifted by the valve operating means to be hereinafter described.

The motor is supported in any suitable manner, such as by means of a frame embodying side members 60, 61 (see Fig. 2). The member 60 is provided with a bearing 62 for receiving the stub shaft 63 of the crank case of one section of the motor, while the member 61 is provided with a bearing for the shaft 65 connected to the other section of the motor and which shaft 65 constitutes the work shaft or to which the propeller may be connected. A thrust bearing 66 is also provided between the member 61 and the adjacent face of the crank case. The crank pin 22 is provided with an arm 67 having a wrist pin 68 which latter is journaled in a suitable bearing 69 for steadyng the crank pin, while the crank pin 20 is also provided with an arm 70 having a wrist pin 71 journaled in a bearing 72.

Referring more particularly to Figs. 2, 7 and 8, the rods 57 are radially disposed along the respective cylinders and terminate just inside of the crank cases and adjacent an annular cam member 73 provided at intervals with cam lugs 74, preferably three in number, while there are employed seven cylinders in each section of the motor. This cam ring, one of which is provided for each section of the motor, is supported by a series of pinion gears 75, 76, which mesh with teeth 77 around the inner face of the cam ring. The gears 76 are preferably idlers while the gears 75 operate to drive or rotate the cam ring from the respective crank shafts through a gear 77 secured to the crank shaft for rotation therewith. This gear 77 meshes with two gears 78 secured respectively to the gears 75 for rotation therewith so that when the cylinders and crank shafts are rotated, the cam ring 73 will also travel or be rotated. The gears and cam ring are preferably arranged on the inside of the crank case to protect them from dirt and grit and at the same time permit them to have a constant lubrication from the oil laden gases, although they may be arranged in any convenient place, and while only one section is described, it is to be understood that both sections are similarly constructed. The driving gears 77 and 78 together with the pinions 75 are so proportioned that the cam ring will travel at a greater rate of speed than the speed of rotation of the cylinders and in the same direction as the direction of the cylinders as indicated by the arrows in Fig. 7, but it is to be understood that whatever the gear ratio may be, it should in all instances be

such that one of the cam lugs 74 will engage the end of one of the rods 57 of each cylinder once during every complete revolution of the cylinder and preferably every time the cylinders reach a predetermined point in their travel, when the engine is a four cycle engine, as in the present exemplification of the invention. The gear ratio is also such as to make the cam lug remain in engagement with the end of the rods a sufficient length of time to permit the waste gases to fully exhaust.

For the sake of illustration and assuming the parts to be in the position shown in Fig. 7, the cylinder marked A is being relieved of the exploded charge and the cam lugs 74 are so arranged and the ratio of the gears is such that one of the cam lugs will next operate upon the valve rod 57 of the cylinder B, then of the cylinder C, then of cylinder D, then of cylinder E, then of cylinder F, and then finally of cylinder G, and each cylinder will be exhausted as the cam acts upon the respective valve rods 57, and the complete action just described above takes place during one complete revolution of the motor section.

With this improved arrangement of parts, it will be manifest that there is not only provided a motor of the four cycle type, but that there will be an explosion in each cylinder for every complete revolution of the cylinder. Taking Fig. 7 for illustration, it will be seen that the cylinder A is exhausting. During the first quarter of revolution of the cylinder, the gases will be expanding, while during the second quarter they will exhaust. The suction of a charge takes place during the third quarter of the revolution, while during the fourth quarter, the gases are being compressed and exploded, thereby producing a motor whereby the maximum number of explosions may be had while there will be one explosion in each cylinder for every revolution of the cylinder, thereby resulting in high efficiency as the greatest amount of power is obtained from each explosion. The latter being accomplished by reason of the fact that the impact is simultaneous upon the moving piston head and moving cylinder head with the result that there is what might be termed a double expansion in each of the cylinders. This is also rendered possible by reason of the fact that the cylinders and cranks rotate in opposite directions and simultaneously. Furthermore, the motor is evenly balanced by offsetting the sections with respect to each other and with relation to the horizontal plane and the gyroscopic force is overcome by reason of the fact that the motor sections rotate in opposite directions. The explosions are caused by the spark plugs 79 which are connected with the usual magneto 80 in a manner well understood in

this art, and which magneto is operated by gears 81, 82 from the shaft 21.

With this improved construction, there will be seven explosions to every complete revolution of each section of the motor and fifteen complete explosions to every revolution of the entire motor and the power strokes will overlap in such a manner as to produce a substantially continuous torque on the work shaft. Another feature of advantage is the fact that the valve operating mechanism is entirely housed, where it is out of the way of dirt and grit.

What is claimed as new is:

15 1. A motor comprising two sections of cylinders and pistons, one of the sections rotating in opposition to the other section, and provisions whereby the rotation of one of the said sections will actuate the pistons of the opposite section.

20 2. A motor comprising two sections of cylinders and pistons, one of the sections rotating in opposition to the other section, and provisions whereby the rotation of one of the said sections will actuate the pistons of the opposite section in opposition to the respective section but in the same direction as the actuating section.

25 3. A motor comprising two sections of cylinders and pistons, one of the sections rotating in opposition to the other section, and piston actuating means operating in opposition to the movement of the respective cylinders and pistons, the piston actuating means of each section being responsive in its action to the operation of the other section of cylinders.

30 4. A motor comprising two sections of cylinders rotatable in opposite directions and about different axes, each of said sections operating to counterbalance the gyroscopic effects of the other section.

40 5. A motor comprising two sections of cylinders having actuating pistons and rotatable in opposite directions and about different axes, said sections being operatively connected, and means for introducing an explosive mixture directly into each section.

45 6. A motor comprising two sections of cylinders rotatable in opposite directions and about different axes, said sections being operatively connected whereby one section will counterbalance the gyroscopic effects of the other section, a piston movable in each cylinder, a rotatable crank for each section and a connection between each of the cranks and the pistons of the respective sections, said cranks rotating in directions opposite to the direction of rotation of their respective cylinders.

50 7. A motor comprising a rotatable section embodying a plurality of cylinders, pistons reciprocable in the cylinders, a rotatable crank connected with the pistons, said crank rotating in a direction opposite to the di-

rection of rotation of the cylinders, and means rotating about a different axis and operatively connected with the rotatable section for counterbalancing the gyroscopic effects of the said section.

70 8. In a four cycle motor of the type described, the combination of two sets of cylinders rotatable in opposite directions, a piston reciprocable in each of the cylinders, and means for causing four strokes between each piston and the respective cylinders upon each complete revolution of the respective cylinders, whereby an explosion will be caused in each cylinder upon every complete rotation of each cylinder, said sets of 80 cylinders rotating about different axes.

75 9. In a four cycle motor of the type described, the combination of two sets of cylinders rotatable in opposite directions, a piston reciprocable in each of the cylinders, and means for causing four strokes between each piston and the respective cylinders upon each complete revolution of the respective cylinders, whereby an explosion will be caused in each cylinder upon every 90 complete rotation of each cylinder, said sets of cylinders rotating about different axes offset with respect to each other.

80 10. The combination of two sets of cylinders rotatable in opposite directions, a piston reciprocable in each cylinder, a crank for each set of cylinders, and a connection between the cranks and the pistons of the respective sets of cylinders, said cranks rotating in the opposite direction from the respective sets of cylinders, each of the cranks being rotatably connected with the other set of cylinders.

85 11. The combination of two sets of cylinders rotatable in opposite directions, a piston reciprocable in each cylinder, a crank for each set of cylinders, and a connection between the cranks and the pistons of the respective sets of cylinders, said cranks rotating in the opposite direction from the respective sets of cylinders, each of the cranks being rotatably connected with and for rotation in the same direction as the said other set of cylinders.

90 12. The combination of two sets of cylinders rotatable in opposite directions, a piston reciprocable in each cylinder, a crank for each set of cylinders, and a connection between the cranks and the pistons of the respective sets of cylinders, said cranks rotating in the opposite direction from the respective sets of cylinders, each crank being rotatably connected with the other set of cylinders, and each of the sets of cylinders and their crank being offset with respect to 115 the other set of cylinders and crank.

95 13. The combination of two sets of cylinders rotatable in opposite directions, a piston reciprocable in each cylinder, a crank for each set of cylinders, and a connection 120

125

130

between the cranks and the pistons of the respective sets of cylinders, said cranks rotating in the opposite direction from the respective sets of cylinders, each crank being 5 rotatably connected with the other set of cylinders, and each of the sets of cylinders and their crank being offset with respect to the other set of cylinders and crank, whereby the axes of rotation of the sets of cylinders

and cranks will be in different horizontal planes.

In testimony whereof I have signed my name to this specification this 30th day of July, 1912, in the presence of two witnesses.

THOMAS P. BROOKE.
